UNITED STATES PATENT OFFICE.

WILLIAM C. CORYELL, OF YOUNGSTOWN, OHIO.

TOY.

No. 822,188.

Specification of Letters Patent.

Patented May 29, 1906.

Application filed September 23, 1904. Serial No. 225,663.

To all whom it may concern:

Be it known that I, WILLIAM C. CORYELL, a citizen of the United States, residing at Youngstown, in the county of Mahoning and State of Ohio, have invented certain new and useful Improvements in Toys; and I do hereby declare the following to be a full, clear, and exact description of the invention, such as will enable others skilled in the art to which it appertains to make and use the same.

This invention relates to improvements in toys, and more particularly to a mechanism for the continuous exploding of paper caps which are formed upon a tape.

15 The object of the invention is to produce a mechanism which will explode the caps while forward movement is imparted to the device.

Another object of the invention is to improve the construction of a toy which may be actuated by manually propelling the same over a surface or by retaining the same in a stationary position and rotating one of its members, thereby imparting movement to the entire mechanism.

25 A still further object of the invention is to construct a simple but efficient toy which can be constructed at a minimum expense.

With these and other objects in view the invention consists in certain other novel constructions, combinations, and arrangements of the parts, as will be hereinafter more fully described, illustrated in the accompanying drawings, and more particularly pointed out in the claims hereto appended.

35 In the drawings, Figure 1 is a view in side elevation showing part of the mechanism in section. Fig. 2 is a sectional view taken on the line A B of Fig. 1, and Fig. 3 is an inverted plan view of the structure illustrated in Fig. 1.

Referring to the drawings, *f* designates the casing of the device, within which is journaled roller *q*, which normally engages a roller *r*. The roller *r* is keyed upon a transverse shaft *d*, which is journaled in opposite sides of the frame or casing *f*. The rollers *q* and *r* are in frictional contact and are positioned in a compartment formed in the casing. A toothed wheel *t* is also keyed upon the shaft *d* within another compartment formed in the casing *f*. The wheel *t* is preferably provided with four teeth, which are adapted to impart a reciprocatory movement to a spring member or hammer *s*, which is positively secured by rivets *k* or the like to the bottom of the frame or casing *f*. The

spring-hammer *s* is provided with a flat end portion *s'*, which is adapted to strike against the anvil *j* for the purpose of exploding the caps which are formed upon the tape *e* as 60 said tape is fed in the direction of the arrow *z* between the rollers *q* and *r*. The teeth of the wheel *t* engage a projection *s²* of spring or hammer *s*, as is clearly shown in Fig. 3. For the purpose of imparting rotary movement 65 to shaft *d* a comparatively large wheel *w* is geared thereto near one end thereof, although it will be obvious that other means could be employed for rotating the shaft *d*. The wheel *w* is adapted to be propelled over 70 a surface by means of the operator grasping the handle *h*, which is positioned within one end of the casing *f*, and manually moving the entire mechanism forward. As the wheel *w* rotates it will impart rotary movement to the 75 shaft *d* and subsequently to rollers *q* and *r* and toothed wheel *t*, consequently feeding the tape *e*, which is adapted to be wound around pin *p* within magazine *p'*, between the frictional rollers *q* and *r* and anvil *j* and portion *s'* of the reciprocating spring-hammer *s*. At each complete revolution of the toothed wheel *t* spring-hammer *s* will be caused to strike the anvil four times, and if the tape which is provided with the caps is in proper 85 position there will have been four explosions upon the completion of each revolution of wheel *t*.

The tape *e* or the like is fed between rollers *q* and *r*, and the edges of said tape are adapted to pass through the recess portions *g* of casing *f*. The recess portions *g* converge throughout their entire length, thereby producing a comparatively wide portion farthest from the anvil, so that the tape is positively 90 fed between the rollers *q* and *r* and subsequently between the anvil *j* and the outer end portion of the vibrating hammer or spring member *s*.

Upon referring to Fig. 2 it will be seen that 100 a portion of the casing extends downwardly in the central part thereof, and upon said extension one of recessed portions *g* is formed. Furthermore, the central extension of the casing fills the intervening space between the 105 roller *r* and the toothed wheel *t*. The roller *q* is journaled in one side of the casing and the central extension thereof.

It will be seen that I have produced a mechanism that is simple in construction 110 and efficient in operation, thereby insuring the employment of the same without liability

of injury to the user. The construction of the handle *h* is entirely optional with the manufacturer, although it is preferable to employ an ordinary straight member.

5 While I have described in the foregoing description and illustrated in the accompanying drawings the preferred construction of my invention, it will be obvious to others versed in the art to which this invention relates that certain alterations, modifications, and changes may be made in the construction of devices in accordance with this invention, and I therefore reserve the right to make such alterations, modifications, and changes as shall fairly fall within the spirit and scope of the present invention.

Having thus fully described my invention, what I claim as new, and desire to secure by Letters Patent, is—

20 1. In a device of the character described, the combination with a casing, a handle secured thereto, of a shaft journaled in said casing, a roller secured to the shaft, a toothed wheel mounted upon said shaft, a driving wheel secured to said shaft, a frictional roller carried by said casing and normally in engagement with said roller secured to the shaft, guiding means formed upon said casing contiguous to said rollers, an anvil formed 25 upon said casing, a spring member having a flat outer end adapted to engage said anvil, said toothed wheel adapted to impart movement to said spring member, and means for supporting tape which is to be passed between the rollers and the anvil and its engaging 30 spring members.

35 2. A detonating-machine, comprising a casing provided with a magazine formed therein near one end, a plurality of rolls, and a toothed wheel journaled in said casing within the forward end thereof, guiding means formed upon each side of said rolls, an anvil secured upon the forward end of said casing, cushioned reciprocatory hammer 40 means carried by said casing and normally in engagement with said toothed wheel and adapted to strike against the anvil, and means secured upon the outside of said casing and connected to said toothed wheel and rolls for 45 imparting movement thereto.

50 3. A detonating mechanism, comprising a casing provided with a hollow end portion and a magazine formed therein, a handle secured within said hollow end portion, a feeding mechanism mounted within said casing, guiding means formed within said casing, an anvil carried by said casing contiguous to 55 said guiding means, a reciprocatory spring-hammer secured to the handle portion of said casing and adapted to engage said anvil, said feeding mechanism normally in engagement with said hammer, and means for imparting movement to said feeding mechanism and hammer.

60 4. In a detonating mechanism, the combi-

nation of a casing provided with an opened base and a hollow end, a handle positioned in said hollow end, said casing provided with a converging recessed portion formed upon each side thereof, a feeding mechanism carried within said casing contiguous to said converging recessed portion, and exploding means carried by said casing and coacting with said feeding mechanism.

70 5. A detonating mechanism, comprising a casing, said casing provided with an opened bottom extending its full length, a handle secured to one end of said casing, a shaft journaled in the opposite end of said casing, a drive-wheel secured to said shaft outside of 75 said casing, a toothed wheel secured to said shaft within the casing, a roller secured to said shaft, a friction-roller secured within said casing above said shaft, an anvil formed upon the outside of said casing contiguous to 80 said shaft, tape-supporting means carried by said casing, a spring-hammer secured to the bottom portion of said casing and extending its entire length, said toothed wheel normally in engagement with said hammer and adapted to cause reciprocal movement of the hammer, when the drive-wheel is actuated.

85 6. In a mechanism of the class described, the combination with a casing, of a transverse shaft journaled within said casing, a 90 drive-wheel secured to said shaft, a toothed member secured to the shaft within said casing, a roller secured to said shaft and spaced apart from said toothed wheel, an anvil formed upon said casing, a spring-hammer 95 provided with a lateral extension secured beneath said casing, the lateral extension of said hammer adapted to be engaged by said toothed wheel, tape-supporting means carried by said casing, and guiding means projecting from opposite sides of said casing.

100 7. In a mechanism of the class described, the combination of a casing having an opened bottom, a shaft journaled in the forward end of said casing, a drive-wheel secured to one 105 end of said shaft, a roller and a toothed wheel spaced apart within said casing and secured to the shaft, a frictional roller mounted within said casing and normally engaging the roller secured to the shaft, a hammer secured to the bottom of said casing, an anvil formed upon the forward portion of said casing, said hammer normally engaging the anvil, and tape-supporting and guiding means carried by said casing.

110 8. A detonating mechanism, comprising a casing having an anvil projecting from the front end thereof, a feeding mechanism mounted within said casing, a drive-wheel positioned upon the outside of said casing and connected to said feeding mechanism, a flexible hammer secured to the rear portion of 115 said casing and capable of engaging said anvil, means carried by the casing for actuating said hammer, and means for supporting an 120

explosive, which is to be fed through said feeding mechanism to the anvil.

9. A mechanism of the class described, comprising a casing, a shaft journaled in said casing, a drive-wheel secured upon the outside of said casing and to one end of said shaft, a toothed wheel secured within said casing and to said shaft, a roller secured to said shaft within the casing, guiding means formed upon each side of said roller and upon one side of said toothed wheel, a frictional roller journaled upon said casing and normally engaging said roller secured to the shaft, an anvil formed upon said casing, a reciprocatory hammer carried by said casing, and means formed upon said casing for supporting an explosive.

10. A detonating mechanism, comprising a casing provided with a central, depending extension, a shaft journaled in each side of said casing, a drive-wheel secured to said shaft outside of said casing, a toothed wheel secured to said shaft between said extension and one side of said casing, a roller secured to said shaft upon the opposite side of said extension, a friction-roller journaled in one side of said casing and the extension, an anvil formed upon said casing, a hammer carried by said casing and normally engaging said anvil, means for actuating said hammer, and means for supplying an explosive to said rollers and anvil.

11. A mechanism of the class described, comprising a casing provided with a central, depending extension, a feeding mechanism positioned within said casing, guiding means formed upon one side of said casing and the extension contiguous to said feeding means, an anvil projecting from one end of said casing, a hammer secured to said casing and coacting with said anvil, means for actuating

said feeding means and hammer, and an explosive-supporting means carried by said casing.

12. A mechanism of the class described, comprising a casing provided with an approximately central depending extension, feeding means positioned within said casing, guiding means formed upon one side of said casing and on said extension contiguous to said feeding means, an anvil formed upon said casing, a hammer secured to said casing and coacting with said anvil, means for actuating said feeding means and hammer, and explosive-supporting means carried by said casing.

13. A detonating mechanism comprising a casing or frame, said casing provided with an anvil, a feeding mechanism provided with a toothed wheel carried by said casing, and a spring-hammer provided with a lateral extension carried by said casing, the lateral extension of said hammer adapted to be engaged by the toothed wheel for reciprocating said hammer.

14. A detonating mechanism comprising a casing or frame, an anvil carried by said casing, a feeding mechanism provided with a toothed wheel carried by said casing, and an integral spring-hammer provided with a flat free end, and an integral lateral extension, fixedly secured at one end to said casing, the toothed wheel adapted to engage the lateral extension of said handle for causing the hammer to reciprocate, when movement is imparted to said wheel.

In testimony whereof I affix my signature in presence of two witnesses.

WILLIAM C. CORYELL.
